UNITED STATES PATENT OFFICE.

ALONZO J. GRIFFIN, OF WILKES-BARRÉ, PENNSYLVANIA, ASSIGNOR OF
ONE-FOURTH TO GEORGE T. GRIFFIN, OF SAME PLACE.

AUTOMATIC RAILWAY-SIGNAL.

SPECIFICATION forming part of Letters Patent No. 542,638, dated July 16, 1895.

Application filed August 7, 1894. Serial No. 519,666. (No model.)

To all whom it may concern:

Be it known that I, ALONZO J. GRIFFIN, a citizen of the United States, residing at Wilkes-Barré, in the county of Luzerne and State of Pennsylvania, have invented a new and useful Automatic Railway-Signal, of which the following is a specification.

This invention relates to automatic railway-signals; and it has for its object to effect certain improvements in automatic signaling apparatus for trains, operated by the passing trains, and adapted to display the necessary signal for regulating the movement of the trains.

With these and other objects in view, which will readily appear as the nature of the invention is better understood, the same consists in the novel construction, combination, and arrangement of parts hereinafter more fully described, illustrated, and claimed.

In the accompanying drawings, Figure 1 is a vertical sectional view of two duplicate signal apparatus constructed in accordance with this invention, one of the signals showing the parts thereof in the position before the train passes, and the other of the signals showing the parts thereof in the position assumed after the train has passed. Fig. 2 is an enlarged detail elevation of the swinging lock-lever and circuit-closer operated thereby. Fig. 3 is a sectional view of a portion of the apparatus showing pneumatic operating mechanism therefor. Fig. 4 is a detail in perspective of another form of operating device for the signal apparatus. Fig. 5 is a vertical sectional view of a series of signals of a modified form employing rotatable semaphore-disks, one of the signals showing the parts thereof in position for displaying the white "safety" signal, the second signal showing the parts thereof in a position for displaying the red "danger" signal, and the third signal showing the parts thereof in a position for displaying the green "caution" signal. Fig. 6 is a detail side elevation of a pair of the semicircular semaphore or signal disks. Fig. 7 is a detail sectional view on the line $x-x$ of Fig. 5. Fig. 8 is a detail plan view of one pair of the semaphore or signal disks. Fig. 9 is a similar view of the other pair of signal-disks. Fig. 10 is a detail sectional view on the line $y-y$ of Fig. 7,

showing the semaphore or signal disks arranged to display the "white" signal. Fig. 11 is a similar view with the disks arranged to display the "red" signal. Fig. 12 is a similar view with the disks arranged to display the "green" signal. Fig. 13 is a diagrammatic elevation of a modified form of releasing device for the lock-lever of the signaling apparatus. Fig. 14 is a side elevation, partly in section, showing another modification of the signaling apparatus. Fig. 15 is a view similar to Fig. 14, showing the parts of the apparatus in position when the signal is displayed.

Referring to the accompanying drawings, 1 designates a tubular signal-tower that is arranged adjacent to a railway-track and is sufficiently high to provide for properly displaying the signal supported thereon, and on top of said signal-tower 1 is mounted a supporting-bracket 2, in which is pivoted at a point intermediate of its ends on the pivot 3 the semaphore or signal-arm 4. The semaphore or signal-arm 4 is provided at one end 75 with a weight 5 that is sufficiently heavy to normally elevate the other wide signal end 6 of said arm, which is painted with the usual signal colors and is adapted to give the proper signals to trains that move over the adjacent track. The weight 5 tends to normally hold the arm 4 in a substantially horizontal position, and at one side of its point of pivot the said arm is provided with the offstanding connecting-stud 7, over which works the upper slotted end 8 of the arm-rod 9, that works within the upper end of the tower 1 and is pivotally connected at its lower end to a vertically-movable weight 10 that works inside of the tower.

The vertically-movable weight 10 is provided with the transverse combined catch and guide-pin 11, the extremities of which preferably project through the guide-slots 12 in opposite sides of the tower to secure a steady movement for the said weight, and connected to the lower side of said weight is the upper end of the lever-rod 13, the lower end of which is pivotally connected to the upper extremity of the lazy-tongs 14, that work within the signal-tower below the said weight. The lazy-tongs 14 are pivotally supported on

the pivot-pin 15, that is secured in a stationary position within the signal-tower and is passed through a pair of the lowermost levers, partly comprising said lazy-tongs, and below 5 the point of pivot 15 the lower end of the lazy-tongs 14 has connected thereto the upper end of the connecting-rod 16, the lower end of which is pivotally connected to one 10 end of the press-lever 17, which partly works within the lower end of the signal-tower. The outer end of the press-lever 17 is pivotally supported, as at 18, beneath one of the rails of the track adjacent to which the apparatus is located, and near its pivoted end 15 the said lever is provided with an upwardly disposed foot 19, lying adjacent to the track-rail in order that the wheels of the cars may pass thereover to provide for depressing the lever 17 to cause the arm 4 to assume its horizontal 20 signaling position.

The depression of the lever 17 by a passing train pulls down on the connecting-rod 16 and causes the lazy-tongs 14 to be distended, which movement quickly elevates the 25 weight 10, and through the medium of the connection 9 with a slotted upper end 8 allows the weight end 5 of the signal-arm 4 to elevate the signal end of such arm to a substantially horizontal position for the purpose of 30 displaying the proper signal, and in this movement the parts of the apparatus are adjusted from the positions shown in signal A of Fig. 1 of the drawings to the positions shown in signal B of Fig. 1 of the drawings. As the weight 35 10 ascends the pin 11 thereof passes to a position above the cam-arm 20, which cam-arm is projected upwardly from an intermediate point of a swinging lock-lever 21, that is pivotally mounted at a point intermediate of its 40 ends, as at 22, at one side of the signal-tower and adjacent to the path of movement of the said pin 11. The swinging lock-lever 21 is provided at one end with a weight 22 that causes the arm 20 to normally assume the position 45 shown in Figs. 2 and 3 of the drawings when the pin 11 has been elevated to the upper end of the slot in which it moves, and the upper end of said cam-arm 20 is rounded, as at 24, to freely ride under and away from the said pin 50 11. It will of course be understood that when the pin is not in its elevated position the same works at one side of the cam-arm 20, so that immediately upon the elevation of the weight 10 to carry the pin 11 above the cam-arm such cam-arm is automatically thrown, by means of the weight 23, directly under the said pin and therefore serves to lock the different parts of the apparatus and to hold the semaphore or signal-arm in its horizontal position 55 until the cam-arm 20 has been thrown from under the pin 11. The end of the swinging lock-lever 21, opposite the weight 23 thereof, has pivotally connected thereto the upper slotted end 25 of the trip-rod 26, the 60 lower end of which is pivotally connected to one end of the armature-lever 27, operated by a pair of electromagnets 28, the wires *a b* of

which are included in a suitable electric circuit to be referred to, so that at the proper time the said magnets will be energized to 70 actuate the armature 27 and release or trip the lock-lever.

Suitably supported in position on the signal-tower directly above the swinging lock-lever 21 is a circuit-closer 29. The circuit-closer 29 essentially comprises the separate insulated bracket-blocks 30, to which are attached the contact-plates 31, and the inner ends of the opposite contact-plates are arranged one above the other and are provided 80 with the contact-pins 32, that are normally separated from each other by the spring of said contact-plates; but when the pin 11 carried by the weight 10 has been lifted to the point where the cam-arm 20 swings beneath 85 the same the said pin will bear against the lower of said contact-plates and cause the contact-pins 32 to come together, and thereby close a circuit over the wires *g h* and *c d*, which wires are included in a circuit with a 90 battery or other generator 33, arranged adjacent to or at a distance from the signal-tower, which electrical circuit also includes the wires *a b* for the electromagnets 28 of the immediately-preceding signal apparatus, as clearly 95 illustrated by the illustration of signals A and B, Fig. 1, this figure being arranged to show two of the signals arranged along the line of the same track and electrically connected by suitable connections, such as diagrammatically indicated.

With the various parts of the signal locked in the set position, as shown in signal B of the drawings, it will now be understood that when the train passes the next signal and 105 closes the circuit through the circuit-closer of that signal, as already described, a circuit will be completed over the wires *g, c, b, a, d*, and *h* and the electromagnets 28 of the "set" signal will be energized, so as to release or 110 trip the lock-lever 21 from the pin 11 and allow the weight 10 to fall and lower the semaphore or signal-arm 4 to the position shown in signal A of the drawings.

While an ordinary form of press-lever 17 is 115 described as connected with the rod 16 for operating the lazy-tongs 14, it will be understood that other forms of operating devices for the signal apparatus, such as shown in Figs. 3 and 4 of the drawings, may be employed. 120

Referring particularly to Fig. 3 of the drawings, it will be seen that a pneumatic operating device is illustrated as connected to the rod 16, such pneumatic operating device being substantially similar to that shown in my 125 former patent, No. 443,440. In this construction the press-lever 17, referred to, is pivotally connected at one end to the upper end of the piston-rod 34 of an air-pump cylinder 35, within which moves a valved piston-head 36, 130 and to the lower end of which is connected a pipe 37, that leads to the bottom of an air-cylinder 38, which, in the present invention, is mounted within the signal-tower at the base

thereof, and accommodates therein a piston-head 39, which is attached to the lower end of the rod 16, that forms the piston-rod therefor, and the said cylinder 38 is provided with 5 a suitable vent-opening 40.

The form of pneumatic operating device just described may be found desirable for use in connection with the apparatus described; but another form of operating device, such as 10 illustrated in Fig. 4 of the drawings, may be employed.

In the form of operating device shown in Fig. 4 of the drawings a rock-shaft 41 is journaled in suitable bearings 42, arranged 15 at one side of the track, and at both ends the said rock-shaft is provided with the rock-arms 43, to one of which is pivotally connected the lower end of the connecting-rod 16, and the other of which is pivotally connected at 20 its outer end, as at 44, to one side of the press plate or bar 45, that is supported by the spring-chairs 46 at one side of one of the rails of the track, and is adapted to communicate motion to the rock-shaft 41 when the car-wheels press 25 thereupon.

In connection with the signal apparatus and the different means for operating the same an ordinary weighted semaphore or signal-arm has been described, but substantially the 30 same operating means may be employed in connection with the form of signals shown in Figs. 5 to 12, inclusive. In these figures of the drawings the signal-tower 1 is illustrated as being provided at its upper end with a semicircular signal-easing 47, that is open at 35 its front side, and accommodates for rotation and concealment therein separate pairs of semicircular semaphore or signal disks 48. The said semicircular disks 48 are arranged 40 in pairs that are displayed one at a time, so that the same signal color may be seen from the track in both directions, and the said disks 48 are mounted on an oscillating shaft 49, journaled in suitable bearings 50 in opposite 45 sides of the semicircular easing 47.

The signal-disks 48 of each pair are reversely disposed to each other, as clearly illustrated in Fig. 6 of the drawings, so that only one disk of each pair can be exposed in front 50 of the easing, while the other disk of the same pair is concealed within the easing, and both sides of the signal-disks are painted, so that by a proper adjustment of both pairs of disks the colors white, red, and green may be displayed at both sides of the signal-tower to be seen from the track in either direction. One pair of the signal-disks 48, which may be additionally designated as 48^a and 48^b, are mounted loosely upon the shaft or spindle 49 55 and are connected at diametrically opposite ends, so as to rotate together, by means of the connecting-bridges 51, that span the space between the said disks, and the other pair of disks, which may be additionally designated as 48^c and 48^d, are mounted fast on the shaft or spindle 49, and are adapted to rotate therewith. One of the semicircular disks of each

pair has pivoted thereto at one side on the pivot 52 a pivoted weight 53, one edge of which rests on a stop-pin 54, projected from 70 one side of the same disk to which the weight is attached, and such weights serve to rotate the said disks in one direction. One disk of each pair of disks 48 is also provided with a peripheral stop-pin 55, that is adapted to engage 75 at the upper and lower front sides of the casing 47 to limit the movement of said disks to a half-rotation, and at one side of one of the disks of each pair is also arranged a winding-pulley 56, to which is connected the upper end 80 of the operating-cords 57 and 57^a, the cord 57 being intended for rotating in one direction one pair of semaphore or signal disks 48, and the other cord 57^a being intended for rotating in one direction the other pair of semaphore or signal disks in a manner to be presently referred to.

The operating-cords 57 and 57^a work inside of the signal-tower 1, and are each connected at their upper ends to a vertically-moving 90 weight 10, already described; but in connection with the rotating semaphore or signal disks it is to be noted that I employ a pair of the vertically-moving weights 10 and the lazy-tongs connections therewith, as well as 95 the automatic lock-lever to engage and disengage the pins of said weights, as has already been fully set forth. The only difference in this double arrangement of operating mechanism for the signals over the arrangement 100 already described is that the lower ends of the connecting-rods 16, that are connected to the lazy-tongs 14, are connected to opposite extremities of a cross-arm 16^a, formed at the upper end of a supplemental connecting-rod 105 16^b, mounted to slide in a suitable guide 16^c, secured within the signal-tower and connected at its lower end to one end of the press-lever 17 previously referred to.

A circuit-closer 29^a, similar to that already 110 described, is arranged in position to be operated by the pin of the weight that is connected to the operating-cord 57^a, and the circuit-wires 115 e f of said circuit-closer 29^a are included in a suitable electric circuit with the battery or other generator 33, which electrical circuit also includes one pair of the electromagnets 28 of a preceding signal, as diagrammatically illustrated in signals C, D, and E of Fig. 5 of the drawings, which figure is arranged to 120 show three signals arranged along the line of the same track and having the necessary electrical circuit connections therewith.

Referring particularly to the signals illustrated in Fig. 5 of the drawings, it is to be 125 noted that the various parts of the apparatus illustrated in signal C are set for an approaching train, and the pairs of signal-disks are so adjusted as to display the white signal. The train in passing the signal C raises the 130 weights through the medium of the connections described and slackens the cords 57 and 57^a, and the pairs of disks will make a half-revolution in response to the weight of the

weights 53, and the said disks will be stopped at a half-revolution by the stop-pins 55, already referred to. When the signal-disks assume this position, the same will expose the 5 red signal, as shown in signal D of the drawings and also in detail, Fig. 14.

After a train has passed a signal with the parts in the position shown in signal C of the drawings, the several parts of the apparatus 10 will be locked in the position shown in signal D of the drawings, and as the train passes the next signal the same action takes place; but the circuit-closer 29^a of this next signal will, through the medium of the connections e', 15 b', a', j, b, a, j, and f, energize one pair of the magnets 28 of the last signal and will release or trip the lock-lever from that weight which is connected to the cord 57^a, so that the parts of the apparatus assume the positions shown 20 in signal E of the drawings, and in this movement the disks 48^a and 48^b will rotate to their former position, and thereby expose the green signal, as may be plainly seen in detail, Fig. 15, of the drawings. In passing the next and third 25 signal the circuit-closer of that signal through the medium of the electrical connections with the first signal, as above traced out, will energize the pair of electromagnets that control the lock device for the weight connected with 30 the cord 57, so that such weight will fall and carry back the disks 48^c and 48^d to their normal positions, again exposing the white signal, as shown in signal C of the drawings.

The means for releasing or tripping the 35 lock-lever 21, as herein already referred to, has simply been a pair of electromagnets with suitable connections; but a mechanical releasing or tripping device, such as illustrated in Fig. 13 of the drawings, may be employed. In this form of releasing or trip device a press-lever 17^a, similar to the lever 17, is employed, and this lever is arranged in connection with the track at any desired distance from the signal-tower, and to one end of this 40 lever is connected an operating-wire 58, that is passed over a suitably-arranged guide-pulley 59 and is connected to one end of a set of lazy-tongs 60, pivotally mounted on the pivot-pin 61, within a suitable box or casing 62, 45 supported on a standard or pole 63, and the end of the lazy-tongs opposite to the pivotal support thereof carries a pulley or roller 64, over which passes a second or extension wire 65, which also passes over a guide-pulley 66, 50 mounted within the box or casing 62, and has connected to one end thereof a weight 67, which assists to maintain the said extension-wire at the proper tension, and the other end of said extension-wire is provided with the 55 branches 68 and 69, from one of which is suspended the weight 70, and to the other of which is connected the spring 71, that is also connected to one end of the lock-lever 21, which is preferably limited in its movement 60 in one direction by means of the stop-bracket 72, secured to the signal-tower and arranged therebelow at one side of its point of pivot.

The branches of the wire 65 pass around suitably-arranged guide-pulleys 73, and it is to be noted that the weights maintain the same 70 at the proper tension, and the spring is employed to allow for different lengths of movement owing to the expansion and contraction of the wire 65, and the lazy-tongs connecting the wires 65 and 58 are employed to compensate for slack wire as well as to speed up the movement of the operating connections. While one set of lazy-tongs has been described, it will be apparent, as clearly illustrated in Fig. 13 of the drawings, that a pair of 75 the same may be used in the line of the connections described, and in this arrangement, as illustrated in the drawings, the continuity of the extension-wires 65 is interrupted and the corresponding ends thereof provided with the 80 weight and pulley connections are connected with one end of both sets of lazy-tongs.

In Figs. 14 and 15 of the drawings is illustrated a modified arrangement of operating means for the semaphore at the upper end of 85 the signal-pole, and by reference to these figures of the drawings it will be observed that an inclined boxing or casing 74 is mounted on the signal-tower at a suitable point above the ground, and the said inclined box or casing 90 accommodates for longitudinal movement therein a set of lazy-tongs 75, that are pivotally secured within the said box or casing on the fixed pivot-pin 76, and to one end of the set of lazy-tongs 75 is connected the lower end 95 of the arm-rod 9, already referred to, and the said arm-rod 9 is connected to the set of lazy-tongs 75 by means of a connecting and guide pin 77, that slides or works in the guide-slot 78, formed in the side of the box or casing 100 and provided at its upper terminal with a horizontal lock portion 78^a. Near the point of pivot the said lazy-tongs have pivotally connected thereto one end of an operating arm or rod 79, which carries at its opposite 105 end the strike-pin 80, guided to move in the longitudinally-disposed guide-slot 81 in the side of the box or casing 74. Pivotally supported within the box or casing 74, at both 110 sides of the pin 80, are a pair of operating bell-crank levers 82 and 83, and to one arm of the lever 82 is attached the upper end of a connecting-rod 84, the lower end of which is connected to one end of the armature-lever 85, working over the electromagnets 86, that 115 are included in a suitable electrical circuit with a track circuit-closer 87, arranged adjacent to one of the rails of the track and adapted to be operated by the wheels of the passing train to close the circuits through the magnets 86, and thereby energize the same. To one arm of the other bell-crank lever 83 is connected the upper end of the connecting-rod 88, the lower end of which is connected 120 to one end of the armature-lever 89, operated by the electromagnets 90, that are included in an electrical circuit similar to the circuit described in connection with the magnets 86, 125 and are similarly energized from a circuit-

closer arranged at a different point along the track from the circuit-closer 87, as will be easily understood.

The downward movement of the rod 84 will move the bell-crank lever 82 in a direction against the pin 80 which will cause the lazy-tongs 75 to be expanded to elevate the semaphore or signal-arm to the position shown in Fig. 18 of the drawings. This movement carries the connecting-pin 77 into the horizontal lock portion 78^a of the slot 78, and this engagement of the pin 77 with the slot extension 78^a serves to lock the various parts of the signal in their set positions, and therefore corresponds to the lock device for the signal, consisting of the lock-lever 21 and its connections. The downward movement of the rod 88 throws the bell-crank lever 83 in a direction against the pin 80 that causes the lazy-tongs 75 to collapse and to release or trip the pin 77 from the slot extension 78^a, so that the semaphore or signal-arm may fall, and the said bell-crank lever 84 and its operating means may properly be said to comprise a releasing or trip device for the locking means of the signal apparatus just described.

From the above it is thought that the operation and construction of the herein-described apparatus, including its modifications, will be apparent to those skilled in the art, and it will be understood that changes in the form, proportion, and the minor details of construction may be resorted to without departing from the principle or sacrificing any of the advantages of this invention.

Having described the invention, what is claimed, and desired to be secured by Letters Patent, is—

1. In a railway signal, the combination with the tower having a guide slot, and the movable semaphore supported on the tower; of a set of pivotally supported lazy tongs carrying a pin working in said guide slot, a connection between said lazy tongs and the movable semaphore, train controlled operating devices connected with the lazy tongs means for locking the pin carried by the lazy tongs at one end of the slot in which it works to secure the lazy tongs distended or expanded, and means for automatically releasing or tripping said pin to allow the lazy tongs to fold, substantially as set forth.

2. In a railway signaling apparatus, the combination with the signal tower having a guide slot, and the movable semaphore supported thereon; of a vertically movable weight working within the tower and provided with a projecting pin extended through and working in said guide slot, a set of lazy tongs pivotally supported within the tower and connected at one end with said weight, train controlled operating connections with said lazy tongs, a lock lever weighted at one end and pivotally supported on the tower adjacent to the movement of said pin, said lever being provided at an intermediate point with an offstanding cam arm adapted to engage

under and against the pin when elevated, and an automatic releasing or trip device for said lock lever, substantially as set forth. 70

3. In a railway signaling apparatus, the combination with the signal tower and the movable semaphore supported thereon; of the vertically movable weight working within the tower and provided with a projecting pin, a set of pivotally supported lazy tongs connected at one end with said weight and at the other end with suitable train controlled operating means, a weighted lock lever pivotally supported adjacent to the movement 75 of said pin and provided with an offstanding cam arm adapted to engage under the pin when elevated, an electro magnet device having an armature lever, a trip rod connected at one end to said armature lever and 85 at its upper end to one end of said lock lever, a circuit closer comprising normally spaced contact plates supported above the pin of the weight and operated by the movement of said pin, and suitable electrical circuits with said 90 circuit closer and said electro magnet device, substantially as set forth.

4. In a railway signaling apparatus, the combination of the signal tower provided at its upper end with a semicircular signal casing, separate pairs of independently movable semaphore disks mounted within said casing, each pair of disks being weighted for rotation in one direction, a pair of vertically movable weights working within the tower, lazy tongs 100 operating connections with each of said weights, suitable connections between each weight and a pair of said semaphore disks to rotate the same in a direction opposite to the inducement of their weights, a locking device 105 for each weight to support the same in their elevated positions, and means for automatically releasing or tripping each lock device, substantially as set forth.

5. In a railway signaling apparatus, the combination with the signal tower provided at its upper end with a semicircular signal casing, an oscillating shaft journaled transversely in said signal casing, separate pairs of semicircular semaphore disks working 115 within said casing and mounted on said shaft, one pair of said disks being loose on the shaft and the other pair fast thereon, and one disk of each pair of disks being provided with a winding pulley and separately controlled 120 operating cords connected to said winding pulleys, substantially as set forth.

6. In a railway signaling apparatus, the combination with the signal tower provided at its upper end with a semicircular signal 125 casing, an oscillating shaft journaled transversely in said casing, separate pairs of semicircular semaphore disks working within said casing and mounted on said shaft, one pair of disks being mounted loose on the shaft and 130 the other pair fast thereon, and the said disks of each pair being reversely disposed to each other, connecting bridges connecting diametrically opposite ends of the disks that are

loose on the said shaft, weights pivoted to one side of one of the disks of each pair, stop pins arranged at one side of said weights, peripheral stop pins for each pair of weights adapted to engage the front sides of the signal casing, winding pulleys connected to one of the disks of each pair, separately operating cords connected at their upper ends to said winding pulleys, and separately controlled

operating connections connected with each of said operating cords, substantially as set forth.

In testimony that I claim the foregoing as my own I have hereto affixed my signature in the presence of two witnesses.

ALONZO J. GRIFFIN.
